UNITED STATES PATENT OFFICE.

HOWARD C. MARMON, OF INDIANAPOLIS, INDIANA.

PISTON.

1,293,846.

Specification of Letters Patent. Patented Feb. 11, 1919.

Application filed July 10, 1916. Serial No. 108,274.

To all whom it may concern:

Be it known that I, HOWARD C. MARMON, a citizen of the United States, residing at Indianapolis, in the county of Marion and

5 State of Indiana, have invented a new and useful Piston, of which the following is a specification.

The object of my invention is to produce an efficient piston, especially designed for 10 use in internal combustion engines, the construction being such as to permit a practical elimination of "slapping" due to the necessity, in piston structures most commonly now in use, of providing sufficient clearance 15 or looseness of fit, throughout the length of the piston to compensate for expansion due to heating.

The accompanying drawings illustrate my invention. Figure 1 is an axial section of 20 my improved piston; Fig. 2 an axial section at right angles to the plane of Fig. 1; Fig. 3 a side elevation in partial axial section of a modified form; and Fig. 4 a section on line 4-4 of Fig. 2.

25 In the drawings, 10 indicates the head, or ring-carrying portion of the piston, provided with the usual circumferential ring-receiving grooves 11, designed to receive packing rings of desired construction.

30 The head portion 10 is comparatively short as to that portion which carries the rings and diametrically may be given sufficient clearance to compensate for all possible increase of diameter due to heating.

35 The head 10 is, however, provided with an axially-extended tubular stem, or shank, 12, of considerably less diameter than the diameter of the ring-carrying portion and at its end this shank or stem is provided with an 40 external circumferential flange 13, which is of less diameter than the ring-carrying portion. At diametrically opposite points, the

45 stem 12 is provided, both externally and internally, with bosses 14 which are bored to form pin-receiving openings 15 for the wrist pin, these bosses being preferably arranged as near the lower end of the shank as possible, as clearly shown in the drawing.

50 The main guide portion or cross-head portion of the piston is formed by an accurately fitted skirt attached to the lower end of the sleeve 12 in such manner that it is, in the main, isolated from the head section, its point of attachment being so remote from 55 that portion of the head of the piston which

is directly affected by the heat, that there will be comparatively little conduction of heat to the skirt, so that the skirt may be made to fit the cylinder very closely.

In Figs. 1 and 2, this skirt section is 60 illustrated as being a single cylindrical shell comprising an upper or inverted skirt 16, a lower depending skirt 17, and an intermediate inwardly-projecting flange 18 mating with flange 13 and attached thereto by 65 bolts 19 and nuts 20, the nuts being tightened and then held in place by peening the end of the bolt. The skirts 16 and 17 may be made very thin and carefully machined inside and out in order to be perfectly balanced. In the form shown in Fig. 3, the 70 upwardly projecting skirt section 16' is formed of sheet metal having an inturned flange 22 at one end and the depending skirt section 17' is also formed of sheet metal and 75 provided with an inturned flange 23 at one end. Flange 22 is formed to fit upon flange 13 of the head section and flange 23 is formed to rest upon flange 22, the two skirt sections being held in place by bolts 19 and 80 nuts 20, as in the other construction. The two skirt sections, having been placed in position, may be accurately externally ground to fit the cylinder into which the 85 piston is to go, and the circumferential crease 24 formed at the junction of the two skirt sections will serve as a reservoir for lubricant.

The upwardly extending skirt section, in 90 either form, extends up close to the larger portion of head 10, but is at all points separated therefrom, so that there can be no direct transmission of heat from the head portion to the skirt. In order to permit the 95 ready insertion of the wrist pin, the upwardly extending skirt 16, or 16', is perforated at 25.

During the operation, there would be an accumulation of oil in the annular space between the upwardly presented skirt 16 and the tubular stem 12, and in order to prevent too great an accumulation of oil, I slit the lower end of the stem 12 at various points by the longitudinal slots 27 which may extend, if desired, entirely through the 100 flange 13 and up far enough to form outlets for the annular space referred to.

In practice I have found that, with the 105 form shown in Figs. 1 and 2, most excellent results can be obtained by making the main 110

body or head portion of the structure of aluminum and the skirt section of cast iron. In the form shown in Fig. 3, the head section may be of aluminum and the skirt sections may be of pressed steel.

In the manufacture of automobile engines at the present time, where the piston speeds are very high, it is very essential that the pistons be not only as light as possible, but 10 that they be as accurately balanced as possible and it is, therefore, important that the skirt section, or sections, be separate from the head section, not only because the necessary stiffness of the skirt member may be obtained by the use of a material different 15 from that used for the head, but also because both the head and the skirt may be carefully machined inside and out and thus proper balancing obtained. No such accuracy of balance could be obtained by a 20 structure in which the skirts were integral with the main body.

I claim as my invention:

1. A piston comprising a head section having a tubular shank of less diameter than the active end and of sufficient length to receive the pitman wrist pin, a skirted cross head section formed independently of the head section, said skirted cross head section comprising an upwardly extended skirt overlying the tubular shank but radially separated therefrom, and also comprising a depending skirt, and also comprising an inwardly projecting portion formed to mate 30 with the tubular stem, and means for fastening the skirted cross head to the head member at a point distant from the active end of said head member.

2. A piston structure comprising a head member having an axially extended portion of less diameter than its active end and provided at the free end of this extended portion with a laterally extended bolt-receiving portion; and a cross head member comprising 40 a skirt portion formed independently of the head member and overlying the axially extended portion of the head member but separated therefrom, and also comprising an inwardly projected portion mating with the laterally projected portion of the head member; fastening bolts connecting said mating portions.

3. A piston comprising a head member having an axially extended portion of less 55 diameter than the active end and provided at the free end of this extended portion with an external circumferential flange; a cross head member having an internal circumferential flange and a skirt portion overlying the axially extended portion of the head member but radially separated therefrom, the said cross head member being formed independently of the head member; headed bolts passing through the flanges of the head 60 member and cross head member with the

heads thereof engaging the flange of the head member, and nuts clamping the cross head member upon the head member.

4. A piston comprising a head member having an axially extended portion of less 70 diameter than the active end and provided at the free end of this extended portion with portions formed to mate with a cross head member; a cross head member comprising a pair of oppositely arranged sheet metal 75 skirts each provided at one end with an inwardly extending flange, the said inwardly extending flanges being formed to mate with each other and with the appropriate portion of the head member, and fastening members 80 clamping the head member and cross head members together.

5. A piston comprising a head member having an axially extended portion of less diameter than the active end and provided at 85 the free end of this extended portion with an external circumferential flange, said axially extended portion having wrist pin receiving perforations between the active end and said circumferential flange; a cross head 90 member having an internal circumferential flange mating with the said external circumferential flange, and having a skirt portion overlying the small extended portion of the head member and extending beyond the 95 wrist pin perforation, said skirt member having perforations permitting the lateral insertion of the wrist pin; and bolts for clamping the cross head member to the head member.

6. A piston structure comprising a head 100 member having an axially extended portion of less diameter than its active end and provided at the free end of said extended portion with a lateral extension; a cross head comprising a mating pair of skirt sections 105 each formed of sheet metal and provided with an inwardly extending circumferential flange at one end, said flanges at their mating planes forming a circumferential crease in the cross head; and means for clamping said 110 inwardly projecting flanges together upon the lateral extension of the head member.

7. A piston structure comprising a head member having an axially extended portion of less diameter than its active end and provided at the free end of this extended portion with a laterally extended bolt-receiving portion; and a cross head member comprising 115 a skirt portion formed independently of the head member and overlying the axially extended portion of the head member but separated therefrom, and also comprising an inwardly projected portion mating with the laterally projected portion of the head member; fastening means connecting said 120 mating portions.

8. A piston comprising a head member having an axially extended portion of less diameter than the active end and provided at the free end of this extended portion with 130

an external circumferential flange, said axially extended portion having wrist pin receiving perforations between the active end and said circumferential flange; perforations between the active end and said circumferential flange; a cross head member having an internal circumferential flange mating with the said external circumferential flange, and having a skirt portion overlying the small extended portion of the head member and extending beyond the

wrist pin perforation, said skirt member having perforations permitting the lateral insertion of the wrist pin; and means for clamping the cross head member to the head 15 member.

In witness whereof, I have hereunto set my hand at Indianapolis, Indiana, this sixth day of July A. D. one thousand nine hundred and sixteen.

HOWARD C. MARMON.
